UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

LOOPER-OPERATING MECHANISM FOR SEWING-MACHINES.

1,111,704.

Specification of Letters Patent. Patented Sept. 22, 1914.

Application filed October 8, 1906. Serial No. 337,992.

To all whom it may concern:

Be it known that I, LANSING ONDERDONK, a citizen of the United States, residing at New York, in the county of New York, 5 State of New York, have invented certain new and useful Improvements in Looper-Operating Mechanism for Sewing-Machines, of which the following is a description, reference being had to the accompanying 10 drawing and to the letters and figures of reference marked thereon.

My invention relates to improvements in sewing machines, and while as to some of its 15 features it may be used for various purposes, said improvements are more particularly adapted to machines for making chain stitches.

The object of my invention is to improve 20 and simplify in certain respects, the looper operating mechanism whereby the looper is given a differential movement.

My invention consists in the novel parts, 25 improvements and arrangements hereinafter shown and described.

In the accompanying drawings which 30 form a part of this specification, I have illustrated one embodiment of my invention, the same serving in connection with the description herein, to illustrate the principles thereof.

Figure 1 is a front elevation of the lower portion of a sewing machine, embodying my 35 improvements the bed plate being removed to more clearly show the looper operating mechanism. Fig. 2 is a view similar to Fig. 1 with the parts operating the looper in a different position. Fig. 3 is a top plan view of my improved looper operating mechanism, certain parts in this view being 40 broken away and shown in section.

In the drawings the base plate 1, the overhanging arm 2, the needle lever extension 3, the needle bar 4, the presser foot 5, the needle 6, and the feed bar 7 are all of the 45 usual construction, and will not require further description.

The looper 8 is mounted on a looper carrier 9, fixedly secured to a looper support 10 by a clamping screw 11. The looper support 50 10 is loosely mounted in brackets 12 and 13, carried by the base plate 1, so that said looper support is capable not only of being oscillated, but of being moved longitudinally. The means for moving the looper

support as shown in the present embodiment 55 of my invention, comprises a sleeve 14, which is clamped to the looper support 10, a rock shaft 15, which is pivoted to a support 16 rising from the bed plate 1 and has one of its arms 17, loosely connected to said 60 sleeve 14. This arm 17 has a split head which freely carries a ball 18, having an opening to receive a stud 19 projecting from the sleeve 14. The rock shaft 15, is oscillated by a link 20, which has a universal 65 connection 21 with the arm 22 of said rock shaft. The link 20 at its opposite end has a universal connection 23, with an arm 24 of a rock shaft pivoted at 25 to a plate 26, mounted on the head of the machine. The 70 opposite end of said rock shaft is pivotally connected to a link 27, which in turn is pivoted to the needle lever extension 3.

It is to be noted that the axis of the rock shaft 15 is arranged at right angles to and 75 at one side of the looper support 10, and therefore the oscillation of said rock shaft will not only oscillate the looper support 10, but will cause said support to move longitudinally. The result of this movement is 80 that the looper in moving forward to take the needle loop is also moved laterally and after the said looper has entered the needle loop, it will be moved laterally across the path of the needle, the looper being slightly 85 curved so as to permit the looper to have such movement. This lateral movement of the looper spreads the looper thread loop for the entrance of the needle on its downward stroke. The arrangement of the pivotal connections between the link 27, the needle lever extension 3, and the rock shaft 28, is such that as the looper reaches the forward end of its stroke said pivotal connections are in alignment with the pivot of the needle lever 90 extension, as shown in Fig. 2 of the drawing. A further movement of the needle lever extension to a position shown in dotted lines in said figure, will give little or no movement to the looper and therefore the 100 looper has an extended dwell at the forward end of its stroke.

The needle lever extension 3 has rigidly secured thereto, a slack thread controlling arm 29, which is provided with thread openings 30. The feed bar 31 has secured thereto a thread finger 32 around which the thread is led in passing to the looper. A

thread guide 33 is also secured to the sleeve 14 through which the looper support is oscillated. This thread guide 33, moving toward and from the path of the thread leading from the slack thread controller 29 to the thread finger 32, serves as an auxiliary thread controller, taking up the slack thread caused by the forward movement of the slack thread controller 29. It will thus be seen that the slack thread controller 29 and the auxiliary thread controller 33 cooperate in keeping the looper thread taut during the entire movement of the looper. The thread finger 32 moving with the feed bar, operates to pull off from the supply thread which is used by the looper in forming the stitch. It will be observed that when the length of the stitch is increased or decreased, that there will be a corresponding increase or decrease in the amount of thread pulled off for the looper.

The slack thread controlling mechanism described herein is of special advantage in high speed machines of the character disclosed, but said controlling mechanism is not claimed herein as the same forms the subject matter of my application Serial Number 337,991 filed of even date herewith.

Various minor changes may obviously be made in the construction set forth in detail without departing from the main principles of the invention and without sacrificing its chief advantages.

Having thus described my invention, what I claim as new and desire to secure by Letters Patent is:—

1. A looper mechanism for sewing machines including in combination, a looper, a looper support, a link, means for reciprocating said link in the direction of its length, and means for connecting said link to said looper support, said connecting means being so constructed as to oscillate said looper support about its axis and to move said looper support longitudinally of its axis.

2. A looper mechanism for sewing machines including in combination, a looper, a support therefor, a link, means for reciprocating said link back and forth in the direction of its length, means for connecting said link to said looper support, said means being constructed so as to oscillate said looper support and move the same longitudinally of its axis for moving said looper into and out of the needle loop, said means for reciprocating the looper being constructed so as to give said looper an extended dwell at the forward end of the stroke.

3. A looper mechanism for sewing machines including in combination, a looper, a support therefor, a link, means for reciprocating the link in the direction of its length, a rock shaft connected to said link and to said looper support, said rock shaft being constructed and disposed relative to

the looper support, whereby said looper support is oscillated about its axis and moved longitudinally of its axis.

4. A looper mechanism for sewing machines including in combination, an oscillating looper, a support therefor, a rock shaft having its axis located at one side of the axis of the looper support and in a plane cutting the axis of the looper support at right angles, means for connecting said rock shaft directly to said looper support including a single pivotal connection, whereby the movement of said connection imparts both an endwise and oscillating movements to said looper support; and means for oscillating said rock shaft.

5. A looper mechanism for sewing machines including in combination, an oscillating looper, a support therefor, a link, a rock shaft connected to said link and to said looper support, the axis of said rock shaft being arranged at right angles to the axis of the looper support, whereby said looper support is oscillated and moved longitudinally, and means for reciprocating said link and giving thereto an extended dwell in its forward position, substantially as described.

6. A looper mechanism for sewing machines including in combination an oscillating looper, a support therefor, a link, means intermediate the link and the looper, whereby said looper support is oscillated about its axis and moved longitudinally of its axis, and means for reciprocating said link, including a rock shaft and device for oscillating the same, whereby said link is given an extended dwell in its forward position; substantially as described.

7. A looper mechanism for sewing machines including in combination, an oscillating looper, a support therefor, a link, a rock shaft connected to said link and to said looper support, whereby said looper support is oscillated about its axis and moved longitudinally of its axis, and means for reciprocating said link including a rock shaft and devices for oscillating same, whereby said link is given an extended dwell in its forward position; substantially as described.

8. A looper mechanism for sewing machines including in combination, an oscillating looper, a support therefor, a link, a rock shaft connected to said link and to said looper support, the axis of said rock shaft being arranged at right angles to the axis of the looper support, whereby said looper support is oscillated and moved longitudinally, and means for reciprocating said link including a rock shaft and devices for oscillating same, whereby said link is given an extended dwell in its forward position; substantially as described.

9. A looper mechanism for sewing machines including in combination, an oscil-

- lating looper, a support therefor, a link, means intermediate the link and the looper support, whereby said looper support is oscillated about its axis and moved longitudinally of its axis and means for reciprocating said link, including a rock shaft, a link connected thereto, and a member connected to said link for operating said rock shaft; substantially as described.
10. A looper mechanism for sewing machines including in combination, an oscillating looper, a support therefor, a link, a rock shaft connected to said link and to said looper support, whereby said looper support is oscillated about its axis and moved longitudinally of its axis, and means for reciprocating said link including a rock shaft, a link connected thereto and a member connected to said link for operating said rock shaft; substantially as described.
11. A looper mechanism for sewing machines including in combination, an oscillating looper, a support therefor, a link, a rock shaft connected to said link and to said looper support, the axis of said rock shaft being arranged at right angles to the axis of the looper support, whereby said looper support is oscillated about its axis and moved longitudinally thereof, and means for reciprocating said link including a rock shaft, a link connected thereto, and a member connected to said link for operating said rock shaft; substantially as described.
12. A looper mechanism for sewing machines including in combination, an oscillating looper, a support therefor, a link, a rock shaft connected to said link and to said looper support for moving said support longitudinally of its axis and for oscillating the same, means for reciprocating said link including a rock shaft and devices for operating the same, the axes of the two rock shafts being arranged at right angles to each other; substantially as described.
13. A looper mechanism for sewing machines including in combination, an oscillating looper, a support therefor, a link, a rock shaft connected to said link and to said looper support the axis of said rock shaft being at right angles to the looper support being at right angles to the looper support whereby said support is moved longitudinally of its axis, and oscillated means for reciprocating said link, including a rock shaft, and devices for operating the same, the axes of the two rock shafts being arranged at right angles to each other; substantially as described.
14. A looper mechanism for sewing machines including in combination, an oscillating looper, a looper support therefor, a link, means intermediate the link and the looper support, whereby said looper support is oscillated and moved longitudinally, a rock shaft to which the opposite end of said link is connected, a needle lever and a link intermediate the needle lever and said last named rock shaft; substantially as described.
15. A looper operating mechanism for sewing machines including in combination, an oscillating looper, a looper support therefor, a link, a rock shaft connected to said link and to said looper support, a second rock shaft connected to the opposite end of said link, a needle lever and a link intermediate the needle lever and said last named rock shaft; substantially as described.
16. A looper operating mechanism for sewing machines including in combination, an oscillating looper, a support therefor, a link, a rock shaft connected to said link and to said looper support, the axis of said rock shaft being arranged at right angles to the axis of the looper support, a second rock shaft connected to the opposite end of said link, a needle lever and a link intermediate the needle lever and said last named rock shaft; substantially as described.

In testimony whereof I affix my signature, in presence of two witnesses.

LANSING ONDERDONK.

Correction in Letters Patent No. 1,111,704.

It is hereby certified that in Letters Patent No. 1,111,704, granted September 22, 1914, upon the application of Lansing Onderdonk, of New York, N. Y., for an improvement in "Looper-Operating Mechanism for Sewing-Machines," an error appears in the printed specification requiring correction as follows: Page 2, line 43, for the word "sail" read *said*; and that the said Letters Patent should be read with this correction therein that the same may conform to the record of the case in the Patent Office.

Signed and sealed this 5th day of January, A. D., 1915.

[SEAL.]

R. F. WHITEHEAD,
Acting Commissioner of Patents.
